UNITED STATES PATENT OFFICE.

JOHN FRANK TEFFT, OF ST. CHARLES, MICHIGAN.

STAMP-VENDING MACHINE.

1,140,210.

Specification of Letters Patent. Patented May 18, 1915.

Application filed July 3, 1914. Serial No. 848,986.

To all whom it may concern:

Be it known that I, JOHN FRANK TEFFT, a citizen of the United States, residing at St. Charles, in the county of Saginaw and State of Michigan, have invented new and useful Improvements in Stamp-Vending Machines, of which the following is a specification.

This invention relates to improvements in stamp vending machines and has particular application to a coin controlled vending machine.

In carrying out the present invention, it is my purpose to provide a coin controlled stamp vending machine whereby upon the application of the proper coin to the machine the latter may be operated to deliver a stamp to the purchaser.

It is also my purpose to provide a stamp vending machine whereby the machine may be operated to deliver and sever stamps from a roll thereof singly in accordance with the number of coins inserted in the machine.

Furthermore, I aim to provide a machine of the class described wherein the mechanism will be self-contained and capable of removal from the casing as a unit so as to facilitate cleaning and repairing of such mechanism.

With the above and other objects in view, the invention consists in the construction, combination and arrangement of parts hereinafter set forth in and falling within the scope of the claims.

In the accompanying drawings; Figure 1 is a view in front elevation of a vending machine constructed in accordance with the present invention. Fig. 2 is a vertical longitudinal sectional view therethrough showing the mechanism in side elevation. Fig. 3 is a vertical transverse sectional view through the machine taken at right angles to Fig. 2 and showing the mechanism in front elevation. Fig. 4 is a vertical sectional view through the receptacle carrying the mechanism showing the side of the mechanism opposite from that illustrated in Fig. 2. Fig. 5 is an enlarged fragmentary sectional view through the machine. Fig. 6 is an enlarged fragmentary side elevation of one of the supporting standards. Fig. 7 is a perspective view of the carrier for the pressure roller. Fig. 8 is a collective view. Fig. 9 is a perspective view of the connecting bar. Fig. 10 is a view in elevation of the feed roller and operating shaft therefor,

parts being shown in section. Fig. 11 is a view in side elevation of the controlling disk. Fig. 12 is a transverse sectional view therethrough. Fig. 13 is a collective view. Fig. 14 is a fragmentary perspective view of a detail of the invention.

Referring now to the drawings in detail, 1 designates a substantially rectangular casing having the front and side open and the rear wall formed, adjacent to the bottom wall, with a vertical opening 2 and hinged to the bottom wall of the casing and movable to a position to close the opening 2 is a cover plate 3 formed with an eye 4 adjacent to the upper extremity thereof adapted to register with an aperture 5 formed in the back or rear wall of the casing 1. Slidable into and out of the casing 1 by way of the open front end thereof is a receptacle 6 carrying the mechanism of the machine and comprising a base or bottom wall 7, side walls 8, 8 standing from the bottom wall and spaced apart in parallelism. The outer faces of the bottom wall 7 and the side walls 8, 8 engage the inner face of the lower wall and side walls respectively of the casing when the receptacle is placed within the latter and closing the outer end of the receptacle is a front wall 9 forming a front wall for the casing. Formed on the opposite side walls of the receptacle adjacent to the front wall 9 and extending across the upper and lower ends of the receptacle adjacent to the front wall 9 are abutment strips 10 designed to 90 abut the outer edges of the side and top and bottom walls of the casing when the receptacle is placed within the latter so as to provide flush surfaces. Formed in the front wall 9 at a point approximately centrally thereof is a delivery opening 11 having an inclined top wall 12 and a concaved lower wall 13 designed to accommodate the fingers of a purchaser.

Arranged within the casing 1 and spaced apart from the rear wall thereof is a vertical partition 14 disposed in contact with the inner edges of the bottom and side walls of the receptacle and forming, in effect, a closure for the receptacle and formed in the partition is a slot 15 spaced apart a suitable distance from the lower end of the partition.

Uprising from the base or bottom wall 7 of the receptacle and disposed immediately behind the front wall 9 at opposite sides of the delivery opening 11 are supporting standards 16 spaced apart in parallelism

and journaled in the standards adjacent to the upper extremities thereof immediately behind the delivery opening 11 is a horizontal shaft 17 and fixed upon the shaft between the standards is a feed roller 18. Formed in the standards 16 immediately below the openings forming the bearings for the shaft 17 and contiguous such openings are substantially rectangular openings 19.

20 indicates a substantially U-shaped yoke having the free extremities of the limbs thereof formed with axially alining circular depressions 21, 21. Formed on the outer faces of the limbs of the yoke 20 and projecting outwardly therefrom are supporting lugs 22, 22 seated within the alining openings 19 in the standards and holding the yoke in position between the standards below the shaft 17, the upper ends of the supporting lugs 22 contiguous the respective curved depressions 21 being formed with curved depressions. Rotatably mounted within these alining depressions are trunnions carried by the opposite ends of a pressure roller 23 and alining axially with each other and with the pressure roller. Fixed upon the outer extremities of the trunnions of the pressure roller are pinions meshing with pinions keyed upon the shaft 17 at the outer sides of the standards so that when the shaft is rotated motion will be imparted to the feed roller and pressure roller simultaneously. Depending from the under surface of the interconnecting member of the yoke 20 and spaced apart are pivot ears formed with axially alining openings 25 having the axes thereof disposed parallel with the standards.

Extending outwardly from the inner face of one of the standards 16 adjacent to the pivot ears 24 is a bracket 26 and pivoted upon the bracket 26 is a bell crank lever 27 having a horizontal limb 28 and a depending vertical limb 29. The outer end of the horizontal limb 28 of the bell crank lever 27 is disposed between the pivot ears 24 and formed with an elongated slot 30 alining with the openings in the ears and passed through these alining openings and slot is a pivot pin forming a pivotal connection between the yoke 20 and the bell crank lever.

Formed in the standards 16 carrying the bell crank lever immediately behind the vertical limb of such lever is an aperture and threaded through the aperture is an adjusting screw 31 having one end thereof in engagement with the vertical limb of the bell crank lever and the opposite end equipped with a manipulating head 32. By means of this construction, it will be seen that when the adjusting screw 31 is rotated in one direction under the action of the head 32 the bell crank lever will be swung about its pivotal connection with the bracket 26 and the yoke 20 elevated with the effect to increase

the frictional contact between the peripheries of the pressure roller 23 and the feed roller 18, while when the direction of rotation of the adjusting screw is reversed the bell crank lever will be swung in the opposite direction to lower the yoke and so decrease the pressure of the pressure roller on the feed roller. The point of contact of the pressure and feed rollers is disposed adjacent to the bottom wall of the delivery opening 11 and upstanding from the base 7 between the forward edges of the standards 16, 16 is a vertical support 33 having the upper end thereof terminating in alinement with the point of contact of the feed roller with the pressure roller and formed with a depression 34 extending the full width thereof and with a rearwardly extending lip 35. Extending rearwardly from the back edges of the supporting standards 16 are arms 36 carrying horizontally alining bearings 37 and journaled in the bearings 37 is a shaft 38 equipped with a reel 39 upon which is placed a roll of stamps of the denomination vended by the machine. Fixed upon one end of the shaft 38 is a pinion 40 meshing with a gear wheel 41 journaled upon a stub shaft carried by the adjacent arm 36 and equipped with a crank handle 42 whereby the gear and pinion may be rotated to revolve the drum to wind and unwind the stamps when desired.

43 designates a horizontal platform disposed between the standards 16 adjacent to the upper ends thereof and alining with the point of contact between the rollers 23 and 18. This platform has the opposite sides thereof downturned as at 44 and provided with apertures whereby the platform may be secured to the confronting faces of the standards at the proper point. Formed integral with the rear edge of the platform or connected thereto in any suitable manner and extending rearwardly therefrom is a horizontal tube 45 substantially rectangular in cross section and having the rear end thereof disposed in proximity to a guide roller 46. Over the guide roller 46 and through the tube 45 is trained one end of a roll of stamps carried by the reel 39, such end of the roll being carried over the platform 43 and between the rollers 18 and 23.

In the present instance, the shaft 17 is coin controlled and the coin controlled mechanism comprises a ratchet wheel 47 fixed to the shaft 17 adjacent to one end thereof and disposed concentrically of such shaft. Mounted upon the upper ends of the standards 16 and arranged transversely thereof and suitably secured thereto is a connecting bar 48 having one edge disposed immediately adjacent to the rear face of the front wall 9 of the casing and formed centrally with a slot or way 49 pivoted upon one end of the connecting bar 48 and normally engaging the teeth of the ratchet wheel 47 is

a spring pressed dog 50 adapted to prevent rotation of the ratchet wheel in one direction. Loosely surrounding the end of the shaft carrying the ratchet wheel 47 and placed in face to face contact with the latter is a disk 51 formed with a radial coin slot 52 opening onto the periphery thereof and a radial shoulder 53 on the periphery thereof approximately centrally of the coin slot. Formed in the disk 51 at diametrically opposite points are arcuate slots 54 and passed through the slots 54 are headed screws 55 threaded into openings formed in the adjacent face of the ratchet wheel 47. Suitably fastened to the outer face of the disk 51 concentrically of the axis thereof and projecting outwardly therefrom is a collar 56 and disposed within the collar 56 and fixed therein is one end of a shaft 57 alining axially with the shaft 17 and having the opposite end thereof projecting outwardly of the adjacent side wall of the casing and equipped with an operating handle 58. Pivoted upon the outer face of one of the standards 16 adjacent to the upper end thereof above the disk 51 and bearing upon the periphery of the latter is a dog 59 having the disk engaging end formed with a rounded edge 60. Projecting inwardly from the inner face of the side wall of the receptacle adjacent to the disk 51 is a pin 61 and pivoted upon the pin 61 and depending therefrom is a vertical arm 62 having the lower end equipped with a weight 63 and the upper extremity formed with an upwardly projecting finger 64 normally engaging a pin 65 secured to the outer face of the disk 51 adjacent to the periphery thereof. The upper end of the casing is formed with a coin slot and leading from such slot into the casing is a coin chute 66 having the lower end thereof disposed in proximity to the periphery of the disk 51 and curved to conform to the configuration thereof. Under normal conditions, the arm 64 is held in engagement with the pin 65 under the action of the weighted arm 62 and the shoulder 53 is held spaced apart from the curved end 60 of the dog 59. When a coin is dropped into the chute 66 such coin gravitates into the radial coin slot 52 in the disk 51 and when the handle 58 is rotated to rock the shaft 57 motion is imparted to the disk 51. In the initial movement of the disk the periphery of the coin engages the rounded edge of the dog 59 and so swings the latter out of the path of movement of the shoulder 53 and in the continued rotation of the disk under the action of the shaft 57 the end walls of the slots 54 engage the screws 55 and so revolve the ratchet wheel 47 and shaft 17 thereby rotating the pressure and feed rollers 23 and 18 with the effect to move the stamp between the feed rollers out of the casing by

way of the delivery opening 11. Disposed in proximity to the periphery of the disk 51 at a point diametrically opposite the chute 66 is a second coin chute 67 having the end thereof adjacent to the disk curved to conform to the curvature of the disk and the opposite end passed through the slot 15 in the partition 14. When the coin slot 52 in the disk 51 registers with the adjacent end of the chute 67 the coin drops into the latter and gravitates into the coin receptacle formed by the back wall of the casing 1 and the partition 14. When the shaft 17 makes one complete revolution the shoulder 53 on the disk 51 engages the dog 59 and so prevents further movement of the shaft, while the pin 65 engages the finger 64. Upon the release of the handle the weighted lever 62 swings the finger 64 and the latter moves the disk 51 through an angle equal to the length of the slots 54 thereby restoring the disk 51 to normal position so that a second coin deposited in the chute 66 will drop into the coin slot 52 in the disk. When the shaft 17 makes one complete revolution as just described the pressure and feed rollers 23 and 18 respectively each make one complete revolution and so slide the strip of stamps over the table or platform 43 a distance equal to the length of one stamp thereby sliding a stamp through the delivery opening 11, the circumference of each roller being such as to move the strip of stamps through this distance upon a complete revolution of the shaft 17.

Formed in the confronting faces of the standards 16 at the forward edges thereof immediately behind the delivery opening 11 are guide grooves 68 and mounted within the guide grooves 68 and capable of vertical sliding movement therein is a knife 69 having a lower cutting edge, such edge is disposed within the groove 34 formed in the upper edge of the support 33. Pivoted connected with the upper edge of the knife 69 and projecting upwardly therefrom is a rod 70 slidably mounted within the way 49 and having the upper end thereof pivotally connected with a horizontal lever 71, such lever having one end pivoted to one side wall of the casing as at 72 and the opposite extremity pivotally connected with a block 73 slidably mounted within a guide groove 74 formed in a supporting block 75 fixed to the upper end of the standard 16 remote from the wall of the casing to which the lever 71 is connected. The lower end of the block 73 is formed with a depending tongue 76 having the lower edge thereof cut at an angle and concaved as at 77. The lower end of the tongue 76 seats within a recess 78 formed in the periphery of a disk 79 fast upon the end of the shaft 17 opposite from the ratchet wheel 47. The concaved end of the tongue normally seats within the recess 130

78 in the disk 79, while the knife 69 normally obstructs the delivery opening 11 and in the rotation of the pressure and feed rollers to deliver a stamp to the purchaser 5 the disk 79 rotates and so elevates the block 73, the latter sliding upwardly within the guideway 74 formed in the supporting block 75. In the upward movement of the block 73 the lever 71 connected thereto 10 swings about the pivot 72 and so elevates the knife 69 through the medium of the connecting rod 70. In the upward movement of the knife the stamp is passed through the delivery opening and immediately succeeding the passage of the stamp into the delivery opening the lower end of the tongue 76 is relieved of the influence of the periphery of the disk 79 and drops into the recess 78 whereby the knife 69 drops to normal position and severs the projecting stamp from the strip. 15

The upper portion of the delivery opening 11 is equipped with a transparent plate 80 whereby tampering with the mechanism 25 is eliminated and the knife 69 immediately behind the transparent plate is formed with a sight opening 81 whereby a prospective purchaser may investigate to determine whether or not the supply of stamps has 30 been exhausted.

In the present instance, the partition 14 and front wall 9 are formed with openings alining with each other and with the opening 5 in the rear wall of the casing and 3 passed through these alining openings is a securing rod 82 having one end headed and the opposite end formed with an eye passed through the opening 4 in the closure plate 3 and designed to receive the hasp of a lock 40 83 so that the parts of the casing will be locked against removal and the coin receptacle maintained closed.

From the foregoing description taken in connection with the accompanying drawings, the construction and mode of operation of my improved vending machine will be readily apparent. When a coin of the proper denomination is deposited in the chute 66, such coin drops into the slot 52 in 45 the disk 51. The shaft 57 may now be rotated to revolve the shaft 17 and in the movement of the pressure and feed rollers to deliver a stamp the knife is elevated and moved out of the delivery opening whereby 50 the stamp will be moved into the delivery opening. Immediately succeeding the passage of the stamp into the delivery opening

the block 73 is relieved of the influence of the periphery of the disk 79 thereby permitting the knife to drop to normal position 60 and sever the projecting stamp from the strip.

While I have herein shown and described one preferred form of my invention by way of illustration, I wish it to be understood 65 that I do not limit or confine myself to the precise details of construction herein described and delineated, as modification and variation may be made within the scope of the claims without departing from the 70 spirit of the invention.

I claim:

1. In a stamp vending machine, a casing having a delivery opening in the front wall thereof, feed and pressure rollers journaled 75 in said casing at the rear of the delivery opening, a shaft carrying said feed roller, driving connections between said shaft and pressure roller, means for actuating said shaft to rotate said rollers, a knife normally 80 obstructing the delivery opening and movable out of the latter in the operation of the feed and pressure rollers, and means operable from said shaft for moving the knife out of the opening and restoring the same 85 to normal position succeeding the operation of the feed and pressure rollers.

2. In a stamp vending machine, a casing having a delivery opening in the front wall thereof, feed and pressure rollers journaled 90 in said casing at the rear of the delivery opening, a shaft carrying said feed roller, driving connections between said shaft and pressure roller, means for actuating said shaft to rotate said rollers, a knife normally 95 obstructing the delivery opening and movable out of the latter in the operation of the feed and pressure rollers, a horizontal lever pivoted within said casing, a connection between said lever and knife, a block connected to said lever and capable of sliding movement, and a disk fixed to said shaft and sliding said block to move the knife out of the opening during the operation of the feed and pressure rollers and restore the knife to 100 normal position succeeding the operation of the feed and pressure rollers.

In testimony whereof I affix my signature in presence of two witnesses.

JOHN FRANK TEFFT.
